UNITED STATES PATENT OFFICE

CLAUDE W. KRESS, OF NEW YORK, N. Y.

DESIGN FOR A GUN STOCK

Application filed August 28, 1931. Serial No. 40,948. Term of patent 14 years.

To all whom it may concern:

Be it known that I, CLAUDE W. KRESS, a citizen of the United States, residing at New York city, county of New York, borough of Manhattan, and State of New York, have invented a new, original, and ornamental Design for Gun Stocks, of which the following is a specification, reference being had to the accompanying drawings, forming a part thereof.

I claim:

The ornamental design for a gun stock, as shown.

CLAUDE W. KRESS.
